METHOD AND APPARATUS FOR COUPLING
A WASHING MACHINE WITH A CENTRIF-
UGAL DRIER

Anton C. Schmelzer, Cleveland, Ohio

Application June 7, 1935, Serial No. 25,456

8 Claims. (Cl. 210—71)

This invention relates to certain new and useful improvements in a method and apparatus for coupling a drier and a wringer-type washing machine, so that the drier substitutes the wringer and is driven by the mechanism employed for driving the wringer.

In wringer-type washing machines an upwardly extended wringer drive shaft, which is coupled with the drive mechanism, operates a 10 wringer gear box, rotatably supported upon a tubular guard of the wringer drive shaft. Some 15 of the wringer-type washing machines also permit of joint uncoupling of the wringer gear box and the wringer from the wringer drive shaft and its guard and this fact is utilized for coupling laundry appliances (ironers, driers, etc.) with the wringer drive shaft by interchanging the wringer gear box and its wringer with such appliances. However this coupling of washing machines with 20 laundry appliances has certain disadvantages, which materially restrict the commercial use of these appliances. Thus only a limited number of the wringer-type washing machines permit of uncoupling of gear box and wringer therefrom; 25 then the appliances to be coupled with the wringer drive shaft in the way above referred to must include coupling means adapted to fit the machine to which the appliance is to be attached; furthermore the appliances must be carried and supported by the tubular guard of the 30 wringer drive shaft, and this often causes the washing machine to become unbalanced and top-heavy; finally the assembly proceedings for coupling the appliances to a washing machine are 35 difficult, it being necessary to raise the appliances substantially above the washing machine, so as to permit the coupling member being extended into and seated upon the tubular guard, and the wringer drive shaft being coupled with the coupling shaft of said member.

It is the primary object of the present invention to provide a simplified method and coupling means for coupling a wringer type washing machine with a centrifugal drier, which method and 45 coupling means are markedly different from presently known methods and constructions in that the coupling method embodies steps which permit of a coupling between the wringer gear box of a washing machine and a drier, and in that the 50 coupling means do not include a coupling member extended into or sleeved upon, and seated upon the tubular guard of the wringer drive shaft of a wringer-type washing machine.

In addition this invention has certain other 55 marked superiorities which radically distinguish

it from the presently known arrangements above referred to. These improvements or superior characteristics embodying certain novel features of construction and combination of parts and certain new steps in coupling a wringer-type washing machine to an extractor are clearly set forth in the following specification and the appended claims; and a preferred form of embodiment of the invention is hereinafter shown with reference to the accompanying drawing forming part of the 10 specification.

In the drawing:

Fig. 1 shows a washing machine and a drying apparatus coupled according to the invention.

Fig. 2 shows an enlarged sectional view through the coupling connecting the wringer drive shaft of a washing machine with the drive shaft of an extractor.

Fig. 3 through 5 show the coupling elements connecting the wringer drive shaft and the drive shaft of the drier prior to their assembly.

Thus Fig. 3 shows the pivotally supported gear box arranged above the top of the drier;

Fig. 4 shows the sleeve coupling and alignment element for the gear box of the drier and the 25 wringer gear box, and

Fig. 5 shows the wringer gear box with the wringer removed therefrom.

Fig. 6 is an enlarged sectional view through one of the legs of the self supporting drier and 30

Fig. 7 is a cross sectional view through the bracket member connecting the washing machine and the drier, the section being taken on line 7—7 of Fig. 1.

Fig. 8 is a cross sectional view on line 8—8 of 35 Fig. 3, showing the arrangement for clamping the gear box to the housing.

Referring more particularly to the drawing, reference numeral 2 denotes a tub or washing receptacle of any suitable construction, which 40 tub is supported on legs 3 and closed at its top by means of a removable cover 4. Within the receptacle 2 and at the bottom thereof is an agitator 5 including a sleeve portion 6 sleeved upon and suitably keyed to a vertical shaft 7, in turn driven from a motor 8. A horizontally disposed main drive shaft 9, leading from motor 8, drives over a worm drive 10 the wringer drive shaft 11, and a rack bar 12, meshing with a gear on shaft 7 and oscillated by an eccentric pin 13 45 on the worm drive 10, oscillates the agitator 5.

The wringer drive shaft 11 and its enclosing tubing 14 lead upwardly to a gear casing 15, which casing sleeves over and is supported by said tubing. This gear casing carries gearing for 50 55

actuating the driven shaft 16, which shaft is normally coupled with the bottom or drive roller of a wringer, not shown. Thus a pair of bevel gears 17, 17', loosely mounted upon the upper 5 end of the wringer drive shaft 11 normally engages with the upper and lower faces of a gear 18, which gear is fixed to the driven shaft 16 by a pin 19. A square outer end on the shaft 16 permits of the shaft being detachably coupled 10 with the lower or drive roll of the wringer, when attached to the gear box. The inner ends of the gears 17, 17' are provided with clutch faces 21, 21' adapted to be engaged by corresponding clutch faces on the ends of an interposed clutch collar 15 22, which is splined upon the shaft 11 to rotate therewith with freedom to move endwise into and out of engagement with the clutch faces 21, 21'.

A rock shaft 23 journaled in a suitable bearing 20 24 carries at its inner end an eccentrically mounted roller 25, which rides in an annular groove 26 in the clutch collar 22 and is adapted to adjust the collar axially into and out of engagement with the gears 17, 17' respectively, and 25 a handle 27 on shaft 23 affords convenient means for operating said shaft.

The tubing 14, which encloses the wringer drive shaft 11, is connected to the tub 2 by means of a bracket 28 and a reduction gearing box 29. 30 The washing machine is coupled with a centrifugal drier 31, including a drive mechanism M, which mechanism is driven from the squared end of the coupling shaft 18 by means of a drive shaft 32. This drier embodies a tank 33, seated upon 35 and secured to the top of a drive housing 34, which housing encloses the drive mechanism M. The drive mechanism in turn supports and is coupled with a rotary basket 35 within tank 33, all as clearly illustrated and described in my 40 pending application Ser. No. 688,513, filed June 11, 1934. The drive housing 34 is mounted on legs 36 having casters 37, which legs are secured to the housing in any common manner. These legs are adjustable in height to permit of vertical 45 adjustment of the drier for horizontal alignment of the respective shafts of the washing machine and the drier as will be later described. Thus each leg 36 slidably supports in its bottom plate 38 a threaded standard 39, held in adjusted 50 position by nuts 40, 40', so as to permit of vertical shifting of the standard with respect to the bottom plate.

The drive mechanism M is driven by means of a drive shaft 41, enclosed in a tubing or housing 55 42, which is supported at its opposite ends adjacent one side of the tank 38 in a bracket 43 and the top of the drive housing 34. The upper end of this shaft is connected with and driven by a gear box 45 which box is swiveled upon the upper 60 end of the tubing 42. The gear box 45 has a lateral extension 44 for the drive shaft 32, which shaft is carried in bearings 46, 47 in said extension and is coupled with the shaft 16 of the wringer gear box 15 by means of a coupling 65 member 48. A tubular alignment member 49, sleeved upon the extension 44 of the gear box 45 and the coupling member 48, aligns the shafts 16 and 32 and their respective gear boxes 15 and 45. Preferably, as shown, the member 49 carries an 70 end plate 50, which is secured to the open end of gear box 15 for closing same instead of the wringer frame, when a wringer is secured to the wringer gear box. The described construction permits of axial adjustments of the shaft 32 with 75 respect to the shaft 16.

When it is desired to couple a wringer-type washing machine with a centrifugal drier, the wringer of the washing machine is disconnected from its wringer gear box and the drier is placed opposite the washing machine and adjusted to proper height by adjusting its legs 36 until the shaft 41 is arranged in the horizontal plane of the shaft 16. Then the two shafts are axially aligned by rotation of the gear box 45 and coupled with each other by the coupling member 48. Thereafter the coupling member 49 is shifted toward the wringer gear casing 15 and secured thereto by means of bolts 51 securing the plate 50 to the gear box 15, it being understood that the plate 50 fits the particular type of gear box to which 15 it is to be secured. Finally the gear box is rigidly secured to the housing 42 by forcing the slotted end 64 of the housing into clamping contact with the cylindrical extension 65 of the gear box 45. The extension 65 extends into the bearing housing 42 and therefore will be rigidly held by said housing, when a nut 66 is screwed home. This nut cooperates with a number of threaded tapered segments 67 welded to or in any suitable manner secured to the slotted end 64 of the bearing housing, that is to the finger portions 68 formed by slotting said housing.

The thus coupled washing machine and drier are rigidly connected to each other by means of a bracket 52 secured to the tubular guard 14 30 and the tubular bearing housing member 42. This bracket comprises two parts 53 and 54, each of which includes a tube clamping seat 55, 56 and a clamping plate 57, 58 respectively, adapted to receive the respective members 14 and 42 and 35 tightly grip same, when nuts 49 of bolts 60 are screwed home. The two parts 53 and 54 overlap each other with their free ends and the part 53 is axially slotted as at 61 to permit of lateral adjustments of the coupling seats 55, 56 with 40 respect to each other until bolts 62, extended through the slot 61 in part 53 and through the part 54 are tightened. Interchangeable, preferably flanged split bushings 63, mounted in the clamping seat 55 of the part 53 permit of proper 45 gripping of the tubular guard 14 of different washing machines, should these guards be of different size and cross section.

Having thus described my invention, what I 50 claim is:

1. In a coupling between a wringer-type washing machine and a centrifugal drier driven means on said drier, means for coupling said driven means with the wringer supporting gear box of the washing machine, and means connected to 55 and laterally extending from said wringer gear box for holding said driven means in alignment with said wringer gear box.

2. In a coupling between a wringer-type washing machine and a centrifugal drier, driven 60 means on said drier, means for coupling said driven means with the wringer supporting gear box of the washing machine, and means connected to and laterally extending from said wringer gear box and aligned with said driven 65 means and said coupling means and axially shiftable with respect thereto for holding said driven means in alignment with said wringer gear box.

3. In a coupling between a wringer-type washing machine and a centrifugal drier horizontally arranged rotatable means coupled with the drive mechanism of the drier, pivotally arranged supporting means for said rotatable means mounted on said drier, means for coupling said rotatable 75

means with the wringer gear box of said washing machine, and means supported upon said pivotally arranged supporting means and connected to the casing of said gear box for holding said 5 casing and said pivotally arranged supporting means in alignment.

4. A coupling as described in claim 3, wherein said alignment means connected to said casing of the gear box are slidably engaged with said 10 pivotally arranged supporting means.

5. In a coupling arrangement for coupling an individual wringer-type washing machine with a centrifugal drier, a gear box supported above the 15 top of said drier and coupled with the drive mechanism of the drier, a shaft laterally extending from said gear box, means slidably engaged with said gear box and connected to the casing of the wringer supporting gear box of the 20 washing machine for aligning said gear boxes in proper working positions, and means enclosed by said aligning means for coupling the laterally extended shaft of said drier gear box with the driven shaft of said wringer supporting gear box.

6. A coupling arrangement for coupling a drier 25 to a wringer type-washing machine, comprising power transmitting means supported above the top of the drier and coupled with its drive mechanism, a shaft laterally extending from said power transmitting means, means axially aligned with said shaft and shiftable with respect thereto for aligning and coupling same with the wringer 30

supporting gear box of the washing machine, and means on said latter means for connecting same to the gear case of said wringer supporting gear box.

7. In a coupling between a wringer-type washing machine and a centrifugal drier rotatable means coupled with the drive mechanism of the drier, pivotally arranged supporting means for said rotatable means mounted on said drier, means for locking said supporting means in adjusted position, means for coupling said rotatable means with the wringer gear box of said washing machine, and means mounted on said supporting means and connected to the casing of the wringer gear box for holding said casing and 15 said supporting means in alignment.

8. In a coupling between a centrifugal drier and a wringer-type washing machine embodying a pivotally supported wringer gear box, laterally extended driven means on said drier and means 20 aligned with said driven means for coupling same with the pivotally supported gear box of the washing machine, said coupling means including a pair of telescoping means axially aligned with said driven means, one of said telescoping means 25 being adapted to be rigidly attached to the casing of said pivotally supported wringer gear box for holding said driven means and said wringer gear box in alignment.

ANTON C. SCHMELZER. 30
